UNITED STATES PATENT OFFICE.

STACY B. HASELTINE, OF CHICAGO, ILLINOIS, ASSIGNOR, BY MESNE ASSIGNMENTS, TO
W. H. MINER, INC., A CORPORATION OF DELAWARE.

HAND BRAKE FOR RAILWAY CARS.

Application filed April 21, 1924. Serial No. 707,824.

This invention relates to improvements in hand brakes for railway cars.

In the operation of hand brakes of the vertical staff type for railway cars, difficulty is sometimes experienced due to the binding of the staff when released, this binding being frequently caused by bulging of the end wall of the car or by bending of the staff itself, with the result that even though the brake is released in the usual manner, the chain will not become fully slack, thereby permitting the brake shoes to remain in contact with the wheels, causing excessive wear and increasing the tractive effort required.

One object of my invention is to provide an arrangement especially adapted for hand brakes of railway cars, wherein provision is made for positively insuring the full and free release of the hand brake mechanism, to the end that the rotation of the staff may not be thereby held and the brake shoes may be free to disengage from the wheels to minimize wear therebetween and reduce the tractive effort required of the locomotive.

Other objects and advantages of the invention will more clearly appear from the description and claims hereinafter following.

In the drawing forming a part of this specification, Figure 1 is a vertical sectional view taken through the end wall of the car and showing my improvements in connection therewith. Figure 2 is a horizontal sectional view of the structure illustrated in Figure 1 and corresponding to the section line 2—2 thereof. Figure 3 is a horizontal sectional view corresponding to the view shown in Figure 2 and showing the dog and release handle in released position. And Figure 4 is a detail plan view of the locking dog.

In said drawing, the end wall of the car is indicated at 10 and a housing or bearing bracket, designated generally by the reference character A, is secured thereto. Said bracket is provided with a rear wall 11 riveted or otherwise rigidly secured to the car wall 10 by means of rivets 17, said bracket also having a bottom web or wall 12 extending horizontally and provided with a journal bearing 13, an intermediate web or partition 14 extending horizontally above the web, and vertical flanges 15 connected toward their front end by a rounded portion 16. A cap or cover plate 18 is also employed and is

preferably held to the bracket casting A by the bolt 28, hereinafter described.

A portion of the usual vertical brake staff is indicated at 19, the same having its upper end 20 squared or of other non-circular cross-section and on which is rigidly fitted a ratchet wheel B. The ratchet wheel B is provided with an upper and a lower set of ratchet teeth, 21 and 22 respectively, the lower end of the ratchet wheel being provided with a journal 23 adapted to rotate within the bearing 13 of the bracket.

Oscillatably mounted on the ratchet wheel B is a carrier or fulcrum member designated generally by the reference character C. Pivotally mounted on the fulcrum member is an operating handle or lever 24, said lever being pivotally connected to the carrier member by means of a pivot bolt 24'. The handle 24 is provided at the top end thereof with a socket 25, within which is slidably mounted a pawl 26 normally impelled outwardly by means of a spring 27. In Figure 1, the operating handle is shown in inoperative position and when it is desired to rotate the ratchet wheel 19 in a step-by-step movement to wind the brake chain on the staff 19, the operating handle is swung vertically to a horizontal position and oscillated, in the usual manner. When the handle is released, it automatically falls to a vertical inoperative position, as shown in Figure 1.

To hold the staff against accidental reverse rotation, I preferably employ the following means: A locking dog designated generally by the reference character D is pivotally mounted between the webs 12 and 14 so as to coact with the set of ratchet teeth 22. This dog is provided with a journal or pivot pin 29 on the upper face thereof, said journal rotatably journaled in a hole 30 provided in the web 14. The forward end of the dog is provided with a tooth 31 to coact with the ratchet teeth 22, said dog also being provided with an elongated slot 32 through which a vertical bolt 28, carried by the bracket, is positioned as shown in the drawing. The dog D is reduced in vertical thickness by having a recess or under-cut portion 33 provided in the under face thereof, the end walls of said under-cut portion forming shoulders 34 and 35 at its ends, extending in a direction substantially radially to the center of the pivot pin 29. A notch 36 is provided radially inwardly of the shoulder 35.

forming a detent at its junction with said shoulder as shown most clearly in Figure 4. When the dog is mounted in the position shown, its tooth 31 will coat with the ratchet teeth 22, and a spring 37 is interposed between the bracket and the toothed end of the dog so as to yieldably force the tooth 31 to coat with the ratchet teeth and permit a step-by-step movement thereof in a winding direction, but prevent accidental reverse rotation thereof.

A release handle or lever 38 is pivotally mounted at its inner end on the vertical bolt 28, said handle being arranged below the dog D and provided with an upwardly extending projection or pin 39 at its inner end adjacent its pivotal axis, this pin serving as a cam and working along the cam surfaces or shoulders 35 and 36 of the dog D in a manner to be hereinafter described. The release handle is bent or offset intermediate its ends and is provided at said bend with an upstanding flange 40, adapted to abut against the fulcrum member or carrier C when the handle is pulled to its position of release as shown in Figure 3.

The operation of the hand brake is as follows, assuming that the parts are in their normal operative position as shown in Figure 2, with the dog tooth 31 coacting with the ratchet teeth 22 and permitting a step-by-step winding movement of the ratchet wheel. In this position, the pin 39 will be closely adjacent or abut against the shoulder 35 so as to enable the release-handle to retract the dog from its engagement with the ratchet wheel while permitting the slight pivoting movement of the dog necessary for the step-by-step movement of the ratchet wheel. When it is desired to release the dog from its holding engagement with the ratchet wheel, the release handle 38 is pulled horizontally to the position shown in Figure 3, when the flange 40 is in a position to be engaged by the carrier or fulcrum member as shown. As the release handle is swung to the latter position, its pin 39 slides along the shoulder 35, acting as a cam to swing the dog in unison therewith, about its pivot 29, the pin 39 seating in the notch 36 at the end of swinging movement of the handle, in which position the tooth 31 is entirely disengaged from the ratchet teeth, and the releasing handle, while in released position, will hold the dog in said released or inoperative position against the pressure of the spring 37.

After the handle has been pulled to its position of release it will remain so, with the pin 39 locked in the notch 36. While in this position the force of the spring 37 acts to tend to oscillate the dog about its pivot 29, this in turn causing the outer side or wall of the notch 36 to exert its thrust 65 against the pin 39 along a line well within

the pivotal axis 28 of the release handle, thus causing the outer end of the handle to be urged toward the carrier member.

While the dog is held inoperative, the brake staff, even though it may stick or bind, during the latter portion of the release of the brakes, will nevertheless be permitted to continue its rotation in an unwinding direction when the car gets in motion and jarring of the brake chain occurs, to permit the brake shoes to become fully disengaged from the wheels and the brake chain to be fully slack.

When the brake is later applied to wind the chain, the brakeman elevates the handle 80 24 and as he oscillates the same, the carrier or fulcrum member C, by engagement with flange 40, will actuate the release handle 38 to cause the pin 39 to move out of the notch 36, whereupon the spring 37 will force the dog into its normal operative position to hold the release handle in its normal position.

I have herein shown and described what I now consider the preferred manner of carrying out my invention but the same is merely illustrative and I contemplate all changes and modifications that come within the scope of the claims appended hereto.

I claim:

1. In a hand brake for railway cars, the combination with a rotatable ratchet wheel adapted to wind a brake chain; of means for rotating said ratchet wheel in a chain-winding direction; a locking dog engageable with said ratchet wheel to prevent reverse rotation thereof; a release handle engaging said dog to hold the latter retracted from the ratchet wheel when said handle is moved to released position; and means whereby said handle is returned to normal position by actuation of said first mentioned means.

2. In a hand brake, the combination with a brake staff having a ratchet wheel rotatable therewith; of means for rotating said staff and ratchet wheel in a step-by-step movement in a winding direction; a spring-influenced locking dog engageable with said ratchet wheel to prevent reverse rotation thereof; and a release handle having a cam portion engaging said dog to actuate the latter out of engagement with said ratchet wheel and hold said dog retracted from the ratchet wheel, said handle and said first mentioned means being arranged to co-act to return said handle to normal position upon operation of said first mentioned means to permit said dog to re-engage with said ratchet wheel.

3. In a hand brake for railway cars, the combination with a rotatable ratchet wheel; of means for rotating said ratchet wheel in a chain winding direction; a spring influenced pivoted locking dog engageable with said ratchet wheel to prevent reverse rota-

tion thereof; and a release lever pivoted about an axis off-set from the pivotal axis of said dog and having means cooperating with the latter to effect movement of the same about its axis in the same direction as the direction of movement of said release lever about its axis, said means being constructed to provide an interlocking connection between said dog and said lever to maintain 10 said dog in retracted position.

4. In a hand brake for railway cars, the combination with a rotatable brake staff having a ratchet wheel thereon; of means for rotating said ratchet wheel in a chain winding direction; a spring-influenced locking dog engageable with said ratchet wheel to prevent reverse rotation thereof; and a release handle having a cam portion engaging said dog to hold the latter retracted from the 15 ratchet wheel when the handle is released, said handle being adapted to lie in the path of movement of said carrier when the former is in released position so that when the carrier is next operated, the latter will engage the handle and move the same to normal position to permit the dog to reengage with the ratchet wheel.

5. In a hand brake, the combination with a rotatable ratchet wheel; of means for rotating said ratchet wheel in a chain-winding direction; a spring-influenced pivoted locking dog engageable with said ratchet wheel to prevent reverse rotation thereof, said dog having a cam surface thereon with a detent 20 portion; and a release handle pivoted about an axis off-set from the pivotal axis of said dog and having a projection coacting with the cam surface of said dog and seating behind said detent portion when the release 25 handle is moved to released position, to thereby hold the dog retracted from the ratchet wheel.

6. In a hand brake for railway cars, the combination with a rotatable ratchet wheel;

of an operating handle for rotating said 45 ratchet wheel in a chain winding direction; a fulcrum member carrying said operating handle; a locking dog engageable with said ratchet wheel to prevent reverse rotation thereof; and a pivoted release handle having 50 its pivotal axis offset from the pivotal axis of said dog and provided with a portion engageable with the dog to actuate the same when the handle is moved to released position, said fulcrum member being arranged 55 to co-act with the release handle to return the same to normal position operating movement of said fulcrum member.

7. In a hand brake for railway cars, the combination with a rotatable ratchet wheel; 60 of an operating lever for operating said ratchet wheel in a step-by-step movement in a winding direction; a carrier member rotatably mounted on said ratchet wheel and carrying said operating lever; a spring-influenced pivoted locking dog engageable 65 with said ratchet wheel to prevent reverse rotation thereof; and a release handle pivoted about an axis offset from the pivotal axis of said dog and engageable with the 70 latter to hold the same retracted from the ratchet wheel, said handle and dog being provided with cooperating camming parts whereby when said handle is moved to release position, said camming parts will exert a camming action to actuate said locking dog about its pivot and hold the latter in released position, against the spring-pressure, 75 said handle being adapted to abut said carrier when the former is in released position, 80 so that when the carrier is next oscillated, the handle will be actuated thereby to move the same and locking dog to their normal position.

In witness that I claim the foregoing I have hereunto subscribed my name this 14th day of April, 1924.

STACY B. HASELTINE.
